UNITED STATES PATENT OFFICE

2,320,443

FUEL DISTRIBUTOR FOR STOKERS

Henry S. Mann, Chicago, Ill., and Eugene Martin, Erie, Pa., assignors to The Standard Stoker Company, Incorporated, a corporation of Delaware

Original application December 2, 1936, Serial No. 113,774. Divided and this application December 6, 1940, Serial No. 368,852

2 Claims. (Cl. 110—105.5)

This invention relates to stokers of the type in which fuel is conveyed from a source of supply to the firing opening in an upright wall of a furnace firebox and is forcibly projected into the firebox and scattered over the firebed.

The primary object of the invention is to provide a novel and efficient fuel distributing apparatus for stokers of the type described.

A type of fuel distributing mechanism that has met with considerable success comprises a table or plate extending forwardly from the discharge end of the fuel delivery conduit of the stoker through the lower portion of the firing opening and into the firebox. A jet head is disposed at the rear of the table and a blast of fluid under pressure issuing therefrom projects the fuel forwardly across the table and into the firebox. Laterally curving upstanding ribs on the forward portion of the table deflect a portion of the fuel to the rear corner portions of the fuel bed. Because of the proximity of the table to the fire bed and the fact that it extends into the firebox, the forward portion thereof burns off to an extent requiring frequent replacement.

It is, therefore, an object of the present invention to provide a fuel distributing mechanism in which fuel is distributed evenly over the entire fuel bed, regardless of the length of the firebox, and at the same time provide a construction requiring infrequent replacement.

Other objects of the invention reside in the novel construction of the parts and in their combination and relation with one another, substantially as described in the following specification and as shown in the accompanying drawing, in which

Fig. 1 is a central vertical longitudinal sectional view through the rear part of a locomotive with a stoker embodying the improved distributing mechanism applied thereto and shown in similar section;

Fig. 2 is an enlarged view in similar section of a portion of the mechanism shown in Fig. 1, and taken on the line 2—2 of Fig. 3; and

Fig. 3 is a sectional plan view taken on the line 3—3 of Fig. 2.

Referring to the drawing, a locomotive is indicated by L and it comprises a boiler 10, having a hollow backwall 11 at the rear of the firebox 12. Within the backwall 11 there is provided a firing opening 9, the lower edge of which is disposed above the firebox grates 13 and also above the plane of the cab deck 14.

Leading forwardly from the tender (not shown) is a conveyor 15 of a stoker which is

indicated generally by S. The conveyor 15 comprises a pair of interfitting telescopic conduits 16, 17; the outer conduit 16 at its forward end is provided with a spherical portion 18 received in a spherical seat 19 of the elbow 20, while the inner conduit 17 provides a bearing for flights 21 of the conveyor screw 22. At the forward end of the conveyor screw 22, the flights 21 are of multiple form in order to facilitate upward movement of fuel through the stoker delivery conduit 23.

The stoker delivery conduit 23 comprises the elbow 20 and a conduit portion 24 received by the upper end of the elbow 20 and firmly secured thereto by means such as the set screw 27. The upper central portion of the forward wall 32 of the conduit portion 24 turns forwardly toward the lower portion of the firing opening 9 and terminates thereof. The rear wall 33 of the conduit portion 24 likewise turns inwardly to form the top wall 34 which merges with the side walls 35, 35a to form the fuel discharge mouth 29. The portion of the firing opening 9 above the top wall 34 is closed by the usual fire-door 36.

Within the lower portion of the firing opening 9, the forward wall 32 is provided at its upper end with a lip 37 forming a seat for the rearward side of a platform 77. Seated partly upon the platform 77 and partly upon the upper surface of the forward wall 32 are a pair of pressure fluid jet members 76, 76a provided with vertical front faces 43 having jet apertures 58. Fluid under pressure is supplied to the jet members 76, 76a by the supply pipes 50.

On its forward side, the platform 77 is provided with a ledge 53 below the upper surface of said platform and upon which ledge 53, a fuel distributing table 75 is seated and secured by suitable means, as the pins 90. The forward end of the table 75 terminates in approximately the plane of the inside sheet of the backwall 11 and since it does not protrude beyond the confines of the firing opening it is protected from the intense heat of the firebox and is not so readily burned off.

In order to control the relative amounts of fuel delivered onto different parts of the table 75 and in front of the jet members 76, 76a, a pair of fuel deflecting vanes 81, 81a are mounted for pivotal movement about upright pins 63, 63a. The vanes 81, 81a are independently operable by means of screws 64 threaded into respective side walls 35, 35a and provided exteriorly of the conduit 24 with operating handles 65.

The rear wall 33 of the conduit portion 24 is provided with an aperture 67, in which aperture an auxiliary jet member 68 is positioned. This auxiliary jet member is provided with jet apertures 72 disposed between the triangular shaped ribs 71. Fluid under pressure is supplied to the jet member 68 through pipes 70, 70a. The fluid issues from the jet apertures 72 at a comparatively low pressure assisting in the delivery of fuel to the main jet members 76, 76a.

The fuel falling onto the table 75 in front of the jet members 76, 76a is projected thereacross by the pressure fluid blast issuing from the jet apertures 58 over the firebed. Since the forward end of the table 75 is disposed approximately in plane of the inside sheet of the backwall 11, the table 75 itself cannot effect a lateral distribution of fuel to the rear sides and corners of the firebox. A pair of deflectors 78, 78a are provided, one at each side of the stoker discharge mouth 29.

Each deflector 78, 78a includes a laterally curved wall 79 depending from a forward end of an arm 80, each wall 79 being arranged to intercept fuel particles projected across the table 75 by the jet members 76, 76a. The rearward end of each arm 80 of the deflectors 78, 78a is secured to a respective fuel deflecting vane 81, 81a. The upper surface of the distributing table is provided at each side of its central, substantially horizontal, unobstructed, flat portion with a forwardly extending inclined portion 85, 85a which portions cooperate to direct fuel forwardly and upwardly against the wall 79 of each of the deflectors 78, 78a.

From the above description it is apparent that the distributing table 75 is protected from the intense heat of the firebox, at the same time a support is provided for the fuel as it is projected to the far reaches of the firebox and its forward path is unimpeded by any part of the distributing mechanism. The corner portions of the fire bed are taken care of by the cooperation of the inclined side portions 85, 85a of the table 75 and the deflectors 78, 78a. Since the deflectors 78, 78a are shielded from the fire by the fuel stream and the stream blast, they are well protected against rapid burning off by the intense heat of the firebox.

The distributing mechanism is thus arranged for maximum protection against burning and consequent replacement and at the same time provides for improved fuel distribution.

This is a division of our application Serial No. 113,774, filed December 2, 1936, now Patent No. 2,228,838. 55

We claim:

1. A stoker for a firebox having an upstanding wall with a firing opening therein, said stoker comprising a fuel feed conduit communicating with said opening, a pressure fluid head at the forward side of the discharge end of said conduit, a table extending forwardly of said pressure fluid head for receiving fuel from said discharge conduit, said table on its upper surface having a pair of laterally spaced sloping portions inclined forwardly and upwardly with respect to the central portion of the upper surface of said table, said pair of sloping portions each having a plane uninterrupted upper surface of greater width than length, said pressure fluid head having a plurality of forwardly directed jet apertures for the emission of blasts of fluid under pressure across the central and inclined portions of said table, and laterally spaced fuel deflecting means above and extending forwardly of the inclined portions of said table for intercepting at least a portion of the fuel projected across the inclined portions of said table and diverting it to the rear corner portions of said firebox.
2. A stoker for a firebox having an upstanding wall with a firing opening therein, said stoker comprising a fuel feed conduit communicating with said opening, a pressure fluid head at the forward side of the discharge end of said conduit, a table extending forwardly of said pressure fluid head for receiving fuel from said discharge conduit, said table having a substantially horizontal, unobstructed central top surface and a forwardly and upwardly sloping portion on each side of said central portion having a plane uninterrupted top surface, said pressure fluid head having a plurality of forwardly directed jet apertures for the emission of blasts of fluid under pressure across the central and sloping portions of said table, and laterally spaced fuel deflecting means above and extending forwardly of the inclined portions of said table for intercepting at least a portion of the fuel projected across the sloping portions of said table and diverting it to the rear corner portions of said firebox, the extended axes of said jet apertures being below the level of said fuel deflecting means and intersecting the plane of said laterally spaced sloping portions of said table.
